US00D530029S

(12) **United States Design Patent** (10) **Patent No.:** **US D530,029 S**
(45) **Date of Patent:** **** Oct. 10, 2006**

(54) **LIGHT BAR**

(75) Inventors: **Steven W. Neufeglise**, Rochester, NY (US); **William H. Dalton, Jr.**, Tulsa, OK (US); **Oriana J. Starr**, Catskill, NY (US)

(73) Assignee: **Star Headlight and Lantern Co., Inc.**, Avon, NY (US)

(**) Term: **14 Years**

(21) Appl. No.: **29/231,672**

(22) Filed: **Jun. 8, 2005**

(51) LOC (8) Cl. **26-06**

(52) U.S. Cl. **D26/28**

(58) **Field of Classification Search** D26/28-36;
362/459-468, 475-478, 485-487

See application file for complete search history.

(57) **CLAIM**

The ornamental design for a light bar, as shown and described.

DESCRIPTION

FIG. 1 is a front elevational view of a light bar in accordance with our design;

FIG. 2 is an end elevational view thereof;

FIG. 3 is a rear elevational view thereof;

FIG. 4 is a perspective view from the rear thereof;

FIG. 5 is a bottom view thereof;

FIG. 6 is a perspective view from the front thereof; and, FIGS. 7 and 8 are front elevational views, similar to FIG. 1, of further embodiments of our design, the other views thereof being line FIGS. 2-7.
